DEVELOPING TANK FOR DEVELOPING
PHOTOGRAPHIC FILMS

Samuel Freeman, New York, N. Y.

Application April 20, 1939, Serial No. 268,883

9 Claims. (Cl. 95—90.5)

My invention relates to a new and improved developing tank for developing photographic films.

One of the objects of the invention is to devise a tank of this kind which can be loaded in daylight and a method whereby said operation can be readily performed.

Another object of the invention is to provide a device of simple and reliable construction which shall be easy to operate and which can be manufactured at low cost.

Another object of the invention is to provide a simple device whereby the exposed film, covered with the protective paper, can be placed within a loading chamber which is located within the tank, and in which all the important operations can be performed after the cover of the tank has been applied and while the cover is in the closing position.

Another object of the invention is to provide a device having a separable loading member into which the film, covered with the protective paper, can be placed. This loading member can then be placed in the loading chamber, and all the subsequent operations are then performed without removing the loading member from the loading chamber or loading portion of the tank.

Other objects of my invention will be set forth in the following description and drawings which illustrate certain preferred embodiments, it being understood that the above statement of the objects of my invention is intended generally to explain the same without limiting it in any manner.

Fig. 1 is a top plan view of the improved device with the cover removed.

Fig. 2 is a vertical longitudinal sectional view of the device, with the cover in its operative or closing position.

Fig. 3 is an elevation, partially in section, on the line 3—3 of Fig. 1.

Fig. 4 is a sectional view on the line 4—4 of Fig. 3.

Fig. 5 is a detail sectional view of the shaft means on which the spools are mounted.

Fig. 6 is a sectional view on the line 6—6 of Fig. 1.

Fig. 7 is a partial detail plan view of the loading member and of the closed rear end of the loading chamber or loading portion of the tank.

Fig. 8 is a top plan view of another embodiment of the guide member which is used for guiding the film from the loading member to the spools.

Fig. 9 is a rear end view of Fig. 8, taken at the left-hand side of Fig. 8.

Fig. 10 is a side elevation of the guide which is shown in Fig. 8.

Fig. 11 is a sectional view, partially in elevation, corresponding to Fig. 2, and showing a different embodiment of the tank.

Fig. 12—18 are detail sectional views, partially in elevation, and illustrating the sequence of operations in utilizing the device.

The device comprises a tank 1 which can be made of "Bakelite" or of any other suitable resin 10 or of any material. At its upper end the tank 1 is provided with a ledge 2. The tank is also provided with a shoulder 3, which is located inwardly of the flange or ledge 2.

As shown in Fig. 1, the ledge 2 and the shoulder 15 3 respectively have the shape of three sides of a rectangle, save that the ledge 2 has rear transverse projections 2a. The cover 4 fits fairly closely, but not liquid-tight, between the flange 2 and the shoulder 3. The cover 4 is provided with 20 a channel-shaped lip 5. This channel-shaped lip 5 consists of a main member which is substantially parallel to the front transverse edge of the cover 4. This main member has two relatively short members which are parallel to the longitudinal edges of the cover. Said main portion of the lip 5 is located behind the right-hand upstanding wall of the lip 3, referring to Fig. 2. The right-hand upstanding wall of the lip 3 is an upward continuation of the right-hand upstanding wall of the tank 1, and the cover 4 is therefore located inwardly of the flange 2, and that portion of the cover which is located at the right of the loading chamber is located between flange 2 and lip 3. The bottom edge of cover 4 35 is indicated by a broken line in Fig. 2.

Referring to Fig. 3, the cover is provided with depending front and rear walls 4a, which are located at the left of the flange 2. As shown in Fig. 2, said cover is also provided with a left 40 end-wall 4b. The cover therefore provides a light-tight closure for the tank.

As shown in Fig. 4, the front longitudinal wall of the tank 1 is provided with a bore or perforation 6. The loading member 7 is also made 45 of "Bakelite" or any other suitable inert material. This loading member 7 is provided with a slot 8 which is open at the rear end of said loading member and which is closed at the front end of said loading member. At the front of said loading member 7, it is closed by a front end-wall 9. Said front end-wall 9 is provided with an integral stud projection 10, and this is provided with an integral reduced stud or projection 11. An annular head 12 is connected to the stud 11 by suitable 50 55

- removable fastening means. A locking arm 14 is provided with an integral sleeve or ring 15, which is mounted turnably upon the larger stud 10. As shown in Fig. 4, the member 9 is located 5 turnably in the bore 8 of the front wall of the tank 1, and said bore or opening 8 of said front wall is provided with a shoulder so as to limit the insertion of the loading member 7 into the tank. Since the sleeve 15 is turnable relative to the stud 10, the locking arm 14 can be turned relative to 10 the loading member. As shown in Fig. 7, the rear longitudinal wall of the tank 1 is provided with a rearwardly extending boss or enlargement 16, which is closed by a rear end-wall 17.
- 15 When the loading member 7 is in its operative position, its open rear end is located turnably in said boss or enlargement 16, whose inner wall serves as a bearing for said loading member 7. The wall of the boss 16 is provided with a bore 21 which has a reduced end-portion. A bullet-shaped latch-member 18 is provided with a head 20 which fits slidably in the bore 21. A compression spring 22 is located between the head 20 and a cap 23 which is screwed into the outer 25 tapped end of said bore 21. The compression spring 22 will therefore hold the latch 18 yieldably in position and the head 20 prevents the latch 18 from being forced out of its bore. The loading member 7 is provided with a cam recess 30 which is aligned with the inner end of the latch-member 18 when the loading member is in the position in which it is desired to lock the protective paper relative to said holding member. In such locking position, the latch-member 18 35 engages the wall of said recess with sufficient force under the action of spring 22 so as to urge one of walls of slot 8 towards the rear end-wall R of the tank, as shown in Fig. 14, for example. The spring 22 then operates to urge the loading member to turn counterclockwise, so as to clamp 40 the protective paper P firmly against the inner surface of rear wall R of the tank and to hold said paper firmly in position. Other spring means can be used to secure this clamping effect. 45 However, by exerting sufficient manual turning force, the loading member can be turned from the position of Fig. 14 to that of Fig. 12. The outer wall of the loading member 7 is provided with an external ridge or rib 24. The front and rear ends of said rib 24 are respectively spaced from the front and rear ends of the loading member 7. The longitudinal wall of the tank is provided with a notch 25, as shown in Fig. 3, through which the rib 24 is pushed when 50 the loading member is inserted into the loading chamber of the device. When the loading member has thus been fully inserted, the rib 24 clears the notch 25 so that the loading member 7 can then be turned clockwise or counterclockwise.
- 55 The inner surfaces of the front and rear longitudinal walls of the tank are provided with upstanding inwardly directed aligned front and rear ribs 26 against which the rib 24 abuts, as shown in Fig. 1, in the release position of the loader which is shown in Fig. 2. This is the position in which the film and the protective paper are unwound from the spool which is located within the loader.
- 60 Referring for example to Fig. 17, when the loading member is turned counterclockwise approximately 180° from the position shown in Fig. 2 to the position of Fig. 17, the rib 24 presses the protective paper P of the film against the 65 inner surface of the rear end-wall R of the tank,

This end-wall R thus serves as a stop to limit the counter-clockwise turning of the loading member from the position shown in Fig. 2. In the position of the loading member which is shown in Fig. 17, the protective paper P is 5 clamped so that it cannot be moved relative to the loading member, and the loading member is held in said clamping position by spring 22.

The tank 1 is provided with a pair of film-holding spools 27 and 27a. These spools are identical. As shown in Fig. 2, the walls of said spools 27 and 27a which face each other, are respectively provided with spiral grooves G. The groove G of each spool 27 and 27a has an inlet end which is close to the center of the respective 15 spool.

Fig. 5 shows a solid rod 28 which is also made of "Bakelite" or other suitable material. At one end thereof, said rod 28 is provided with integral spaced heads 29 and 30. At said end, the rod 20 28 is provided with a tapped recess 31. An externally threaded sleeve 32 is mounted upon the inner rod 28. One end of said sleeve 32 abuts the head 29. The washer 33 is held against the other end of the sleeve 32 by means of a clamping 25 screw 34 whose shank is located in a tapped recess of the rod 28. The head of the screw 34 serves as one of the bearings for the assembled rod 28 and sleeve 32.

As shown in Fig. 1, the front and rear members 30 of the shoulder 3 are provided with vertical recesses which extend downwardly from the top wall of said shoulder 3, and in which the head 35 of the member 34 and the head 30 are respectively turnably located.

The rod 28 and the sleeve 32 have corresponding transverse slots 35 and 35a, as shown in Fig. 5. The inner end of a flexible strap 36 is located and held in said slots 35 and 35a, so that the members 28 and 32 turn in unison. Said strap 36 is made of rubberized material, or other material which is inert to the developing and fixing solution. When members 28 and 32 are turned in unison in one direction, the strap 36 is wound spirally around the sleeve 32. The outer end of the strap 36 is provided with a clamp 37.

Means external to the tank are provided for turning the members 32 and 28 in unison with the holding spools 27 and 27a. As shown in Fig. 1, a rod 38 which is externally threaded at its inner end, is screwed into the recess 31 of the rod 28. A washer 39, made of rubber or other suitable material, is mounted on the rod 38. A head 40 is also mounted on said rod 38 and said head 40 compresses the washer 39 so as to produce a liquid-tight joint at the front longitudinal wall of the tank. A knob 41 is connected to the outer end of said rod 38. When the knob 41 is turned, it turns the members 28 and 32 in unison with the spools 27 and 27a.

As shown in Fig. 1, the outer wall of the externally threaded sleeve 32 is provided with a series of spaced recesses 42. Each of the spools 27 and 27a has a hub 43, which is clearly shown in Figs. 1 and 6. Each hub 43 is provided with 65 a latch-member 44, which is pressed inwardly by a compression spring 45, which is held in place by means of a removable threaded plug 46. When the latch member 44 enters one of the recesses 42, the respective spool 27 or 27a turns 70 in unison with the members 28 or 32. The spools 27 and 27a can thus be adjusted towards or away from each other so as to accommodate films of varying width.

The guide member 47 is provided for leading 75

the film from the slot 8 of the loading member 7 to the inner ends of the grooves G.

As shown in Figs. 1 and 2, the guide member 47 is provided with ribs 48 which are integral with upstanding projections 49, which are integral with the left-hand edge of the guide member 47. The ribs 48 are angular, as shown in Fig. 1, so that the film is led between guide member 47 and the longitudinal parallel portions of ribs 48. Said upstanding projections 49 are provided with lugs 50 which enter vertical recesses 51 of the front and rear walls of the flange 3. Said recesses 51 are open at their upper ends. The guide member 47 can thus be detached from the device. It normally occupies the position shown in Fig. 2, in which it abuts the sleeves 32 or the hubs 43, depending upon the spacing between the spools 27 and 27a. The guide member 47 is turnable relative to the tank. Adjacent the sleeve 32, each of the spools 27 and 27a is provided with radial spaced arms 52, so that the liquid can pass through the spaces between said arms.

Guides of different widths may be used in connection with the device in order to accommodate films of different widths.

Figs. 8-10 show an improved guide 47a whose width can be adjusted. Said guide consists of two members 53 and 54, having hubs through which a cylindrical rod 55 is passed. These hubs have set screws 56 so that said hubs can be clamped adjustably on the rod 55 so as to adjust the space between said members 53 and 54.

As shown in Fig. 8, the member 53 has an angular arm 56a connected thereto. A series of spacing members 57 are mounted on said arm 56a. Said arm 56a is provided with an enlarged head 58. The adjacent surfaces of these spacing members 57 have interfitting tongue-and-groove joints. By varying the number of spacing members 57, the effective width of the guide 47a can be adjusted.

The modified guide 47a shown in Figs. 8-10 has counter-weights 59. The ends of the member 55 are equivalent to the members 50 of Fig. 1. The counter-weights 59 are sufficiently heavy to normally hold the guide 47a in a substantially horizontal position. In such position, the angle between the guide 47a and the horizontal plane is smaller than the angle between the guide 47a and the horizontal plane when the film has been fully threaded into the grooves G. Therefore, when the film has been fully threaded into the grooves G and said film has wholly cleared the guide 47a, the counter-weights 59 slightly tilt the guide 47a towards the horizontal plane. Therefore, if the spools 27 and 27a are now turned reversely or counterclockwise, the rear end of the film will not strike the guide 47a. A rod 60 is connected to one of the counter-weights 59.

When it is desired to diminish the width of the guide 47a, in the embodiment of Figs. 8-10, one or more of the spacing elements 57 can be turned reversely on the arm 56a, to rest upon the arm 60.

The embodiment shown in Fig. 11 is substantially the same as that shown in Fig. 1, save that in Fig. 11 the loading chamber has a bottom convexo-concave all 62 upon which the loader 7 rests turnably. In the embodiment of Fig. 11, as in Fig. 1, bearings are provided for the loader 7 in the front and rear longitudinal walls of the tank 1.

The tank is provided with a lip L by means of which liquid can be poured out of said tank.

The method of using the device is as follows:

The cover 4 is removed and the strap 36 is pulled out to its maximum extent and it is led over the right-hand end-wall of the tank. A suitable quantity of developing solution is then poured into the tank. Ordinarily it is sufficient to fill the tank to about one-half its height.

The roll of film is of the usual type. This includes the usual film F, to whose front end a short pull-strip of paper P' is connected in the well-known manner. This is usually done by adhesive. In addition, the roll of film is provided with the usual long strip of protective paper P, which, together with the film F, if wound spirally around the shank of the spool 11. The strip of paper P is longer than the film and it is connected to the rear end of the film by means of a short strip of cloth 10. This strip of cloth 10 is connected to the rear end of the film F and to the protective paper P, by means of suitable adhesive.

While the cover is detached from the tank, the loader 7 is removed and the roll of film is placed into the loader, through its open rear end. The loader is now placed in the position shown in Fig. 12. The front end of the paper strip P is now pulled so as to turn the roll of film. This strip of protective paper P is led towards the left-hand or rear end-wall R. After a sufficient length of the paper P has been unrolled, the paper strip P' is exposed, as shown in Fig. 13. The paper strip P' is led in a direction reverse to the direction of the strip P. This can be done by placing a pencil or other suitable instrument upon that part of the paper P which is still in the rolled-up condition, so that the strips P and P' are respectively led in opposite directions.

As soon as the paper strip P' has been exposed and before any part of the film has been exposed to the light, the loader 7 is turned counterclockwise to the position shown in Fig. 14 from the position shown in Fig. 12, so as to shut off the light from the film, even though the cover 4 is off the tank. The clamp 37 is now connected to the pull strip P'. The belt 36 now overlies the guide 47 with part of said belt 36 contacting with the guide 47. The cover 4 is now replaced and locked so as to shut off light from the film.

The loader 7 is then turned to the position shown in Fig. 15, this being the same as the positions shown in Figs. 12 and 13. The knob 40 is now turned so as to turn the spools 27 and 27a, thus winding up the strap 36 around the sleeve 32 and leading the film into the grooves G of the holding spools 27 and 27a.

At the same time the paper P is pulled away from the left-hand end-wall R of the tank so that the paper P is continuously separated from the film as the film is led into the grooves G. As shown in Fig. 15, when the cover 4 is placed upon the tank, the free end of the protective paper P projects to the left of the cover. While the strip of paper P' can be removed and the clamp 37 can directly grip the end of the film, it is preferable to retain the strip P'. As the film is collected in the grooves G, the angle between the guide 47 and the horizontal plane is diminished. When the connecting cloth strip 10 is moved into the position shown in Fig. 16, thus clearing the loader the operator feels an increase in the tension. The operator then moves the loader to the position shown in Fig. 17 so that the loader clamps a part of the paper P against the wall R of the tank, leaving the cloth strip 10 perfectly free. Sufficient pull is exerted upon the strip P 75

so as to separate the same from the cloth strip 70, while the member 40 is turned simultaneously to continue the winding-up of the film in the grooves G. The adhesion between the cloth strip 70 and the film F is greater than the adhesion between the cloth strip 70 and the paper strip P, so that the cloth strip 70 remains adhering to the film F.

After the strip P has been separated from the strip 70, the loader is moved back to the position shown in Fig. 18 and the paper strip P is completely removed from the apparatus and the film F is located wholly in the grooves G. The loader is then turned counterclockwise to the position shown in Fig. 14, so that when developing, none of the developer will get into the loader 7. The counter-weights 59 tilt the guide 41a so as to diminish the angle between said guide and the horizontal plane. The latch 18 and the spring 22 have sufficient force to keep the loader firmly in the respective positions shown in Fig. 17 and in other figures.

The locking device for the cover is shown in the inoperative position in full lines in Fig. 3 and in the operative position in broken lines in Fig. 3.

The cover 4 is provided with a boss 80 which is engaged by the arm 14, when this is in the broken-line position shown in Fig. 3. In said locking position the arm 14 abuts a stop 81. After the film has thus been wholly taken up by the spools 27 and 27a, the spools 27 can be turned back-and-forth by operating the knob 40 so as to agitate the developing solution and to develop the film thoroughly. The developing solution is then poured out without removing the cover 4, using the lip L. Water is then poured into the tank and the film is then agitated until it has been thoroughly washed.

The wash water is then poured out through the lip L, the film being held in position in the grooves G. Fixing solution is then poured into the tank and the film is agitated until the fixing operation has been completed. The cover is now removed and the fixing solution poured out. After the film has been fixed, the cover can be removed, and the film can be readily removed from spools 27 and 27a.

It will be noted that the guide is wholly free from the spools or discs 27 and 27a, and that no part of said guide engages the grooves of the members 27 and 27a. It will also be noted that the device has a single loading chamber.

While I prefer to use a turnable loading device, the invention is not limited to the use of a loading device which is turnably mounted in the tank. Likewise I prefer to use the clamping means illustrated herein but I can use any other type of clamping means for preventing film from accidentally unrolling, when the clamp member 37 is connected to the pull-strip P'. For example the clamping means can be mounted on the loader itself. Likewise by careful manipulation, it is unnecessary to hold the pull-strip P' against moving when the clamp 37 is connected thereto. The principal feature of the invention is that a single loading chamber is utilized and the clamp is connected to the pull-strip while the film and the protective strip P are wound spirally on the shank of the spool 71.

In utilizing the device, the spools or film take-up means 27 and 27a are oversized, so that when the film is located wholly in grooves G, the top of the film in said grooves is located at a level which is below the level of the pivot of the guide 41 or 41a. Hence, when the film has fully

cleared guide 41a, its counterweights turn the guide 41a upwardly, so that said guide 41a wholly clears the film in grooves G.

The width of the guide between the inner walls of members 48, is slightly less than the width of the film, so that the cross-section of the film is concavo-convex when the film is fed into grooves G. The film straightens, due to its elasticity, as it is fed into grooves G.

The space between cover 4 and wall R may be designated as means for feeding the strip P out of the tank. Other outlet means may be substituted.

A cover which is hinged to the tank is equivalent to a removable cover, within the scope of the claims.

The wall R may be designated as means for closing the slit in the loading device when said loading device is in predetermined position. The members 18 and 22 are resilient means adapted to hold said loading member releasably in said predetermined position.

One of the important features per se of the invention is that, in the embodiment of Figs. 8-10, the counter-weights tilt the guide upwardly when all the film has been taken up by the spools, and this feature can be used with a guide of any type, adjustable or non-adjustable, and without the spacers of Figs. 8-10.

I claim:

1. In a daylight-loading device, a development tank which has a top edge-wall and a removable cover at said top edge-wall, the sub-combination of a loading device, said tank having means located below its top edge-wall and constructed to hold said loading device turnably in position below said top edge-wall, said loading device being shaped to hold thereon a spool on which a roll of film and a protective strip of paper are jointly wound spirally, said loading device having a slit in its wall through which said protective strip and said film can be jointly led and unwound from said spool, film take-up means turnably mounted in said tank, first means adapted to feed the film away from said slit to said take-up means, second means adapted to lead the paper strip out of the tank and between said top edge-wall of the tank and said cover, when the cover is in operative position, said slit being sufficiently narrow to retain the spool within said loading device, said loading device having an opening other than said slit through which the spool and the roll of film and protective paper can be inserted into said loading device, said cover being removable independently of said loading device.

2. A daylight-loading developing tank having a removable cover, a loading member insertable into said tank and removable therefrom, said loading member being located below said cover when it is inserted into the tank, said tank having means constructed to hold the loading member turnably when the loading member is inserted into said tank, said loading member having a slit in its wall through which a film can be fed, film take-up means turnably located in said tank, a pull device connected to said take-up means and constructed to pull film away from said slit towards said take-up means, operating means external to said tank and constructed to operate said take-up means and said pull device in unison, the interior of said tank having means adapted to close the slit in said loading device when the loading device is turned to a predetermined position, said loading device having an outer end-wall.

3. In a daylight-loading developing tank, the sub-combination of a loading member which is insertable into said tank and which is removable from said tank, said tank having means to turnably support said loading member when the loading member is inserted into said tank, said loading member having a slit in its wall through which the film can be led, said tank having additional means located therein and adapted to close said slit when the loading member is turned to a predetermined position.

4. In a daylight-loading developing tank, the sub-combination of a loading member which is insertable into said tank and which is removable from said tank, said tank having means to turnably support said loading member when the loading member is inserted into said tank, said loading member having a slit in its wall through which the film can be led, said tank having additional means located therein and adapted to close said slit when the loading member is turned to a predetermined position, said tank having resilient means adapted to hold said loading member releasably in said predetermined position.

5. In a daylight-loading developing tank, the sub-combination of a loading member which is insertable into said tank and which is removable from said tank, said tank having means to turnably support said loading member when the loading member is inserted into said tank, said loading member having a slit in its wall through which the film can be led, said tank having additional means located therein and adapted to close said slit when the loading member is turned to a predetermined position, said additional means and said loading member being constructed to clamp an intermediate strip.

6. In a daylight-loading developing tank which has a removable cover, the sub-combination of means adapted to support a film within the tank, movable film take-up means located within the tank, a pull device constructed to pull film towards said take-up means, said pull device and said take-up means having operating means which are located external to the tank, said film take-up means comprising a pair of turnable members having spiral grooves whose inlet ends are located adjacent the axis of rotation of said turnable members, a film guide turnably mounted

in said tank and shaped to lead the film towards said grooves, means adapted to hold said guide yieldingly in a position in which its edge is located above the top of the film which is located in said grooves.

7. For use in a daylight-loading developing tank, a guide having means constructed to connect the same turnably to the tank, said guide including a pair of laterally adjustable main members and intermediate spacing members, said spacing members being turnably connected to one of said main members so that one or more selected spacing members can be turned out of operative position, said main members being movable towards each other and away from each other.

8. For use in a daylight-loading developing tank, a guide having means constructed to connect the same turnably to the tank, said guide including a pair of laterally adjustable main members and intermediate spacing members, said spacing members being turnably connected to one of said main members so that one or more selected spacing members can be turned out of operative position, said main members being movable towards each other and away from each other, one of said main members being supplemental means adapted to hold the spacing members in their inoperative positions.

9. A daylight-loading developing tank having a removable cover, a loading member insertable into said tank and removable therefrom, said tank having means adapted to turnably support said loading member when the loading member is inserted into said tank, said loading member having a slit in its wall through which a film can be led, said tank also having turnable film take-up means, said tank having first stop-means adapted to hold said holding member in a first position in which its slit is located operatively relative to said take-up means, said tank having second stop-means constructed to limit the turning movement of the holding member away from said position to a second predetermined position, said tank having closure means constructed to close said slit when the holding member is in the second predetermined position.

SAMUEL FREEMAN.
